Primary Examiner — Susan Bennett Hattan*Assistant Examiner* — Brett Miller(74) *Attorney, Agent, or Firm* — Pate Peterson PLLC; Brett Peterson(57) **CLAIM**

I claim the ornamental design for the etching tray with lid, as shown and described.

DESCRIPTION

FIG. 1 is a front view of the lid attached to the tray.
FIG. 2 is a top perspective view of the lid attached to the tray.
FIG. 3 is a top perspective view of the lid.
FIG. 4 is a front side view of the lid.
FIG. 5 is a back side view of the lid.
FIG. 6 is a top view of the lid.
FIG. 7 is a bottom view of the lid.
FIG. 8 is a left side view of the lid.
FIG. 9 is a right side view of the lid.
FIG. 10 is a bottom perspective view of the lid.
FIG. 11 is a top perspective view of the tray.
FIG. 12 is a front side view of the tray.
FIG. 13 is a back side view of the tray.
FIG. 14 is a top view of the tray.
FIG. 15 is a bottom view of the tray.
FIG. 16 is a left side view of the tray.
FIG. 17 is a right side view of the tray; and,
FIG. 18 is a bottom perspective view of the tray.
The broken line portions of the etching tray with lid are not claimed as part of the claimed design.

1 Claim, 18 Drawing Sheets---
